UNITED STATES PATENT OFFICE.

WILLIAM P. BRETT, OF DECATUR, ILLINOIS.

WINDMILL.

1,105,020.

Specification of Letters Patent.

Patented July 28, 1914.

Application filed April 27, 1904. Serial No. 205,208.

To all whom it may concern:

Be it known that I, WILLIAM P. BRETT, a citizen of the United States, residing at Decatur, in the county of Macon and State of Illinois, have invented certain new and useful Improvements in Windmills, of which the following is a specification, reference being had therein to the accompanying drawings.

10 My invention relates to that class of windmills in which the fans or sails of the wind-wheel are pivotally mounted and adapted to be turned either full into or entirely out of active position, and has especial reference to 15 that class in which the wheel shaft is mounted in a substantially horizontal position and is carried by a main frame or turntable which is so mounted as to be rotatable about the vertical center line of a vertically apertured pivot portion which constitutes the 20 bearing part of said turntable and is so designed that the power of the mill may be transmitted therethrough by means of either one of a variety of power transmitting devices whereby the mill is adapted to do various 25 kinds of work; and the objects of my improvements are, first to provide a windmill of great strength, of light weight, and comprising in its construction speed regulating devices that are adapted to maintain 30 a substantially uniform speed in the rotation of the windwheel during irregular winds and while carrying variable loads that come within its capacity; second to provide means 35 for putting the fans or sails of the wheel into or out of active position that have no retarding frictional contact with any of the parts that rotate with the wheel or its shaft when said fans or sails and the governing 40 devices operative in connection therewith are relieved and in their normal operating condition; third to provide means for the reduction of the friction of the power transmitting mechanism to a minimum; fourth to 45 so construct the power transmitting mechanism that while in operation it has, during light winds, no frictional or retarding abrasive action or any of the devices employed in putting the fans or sails into and out of 50 active position; fifth to provide means by which the most important parts of the said governing and power transmitting mechanism is automatically lubricated and protected by an inclosing incasement; sixth to 55 provide means by which a windmill of the type herein described may have its oil sup-

plies replenished while the mill is in operation and without the necessity of having to climb the tower; seventh to so construct a windmill that it can be so adjusted as to automatically care for itself in handling work that requires a certain and regular speed for its proper performance, by standing inactive until there is sufficient wind for a surplus of power over and above that which is barely sufficient to carry the load; and eighth to provide a windmill embodying in its construction all of the above mentioned features in a harmonious whole such as may be safely allowed to do its work and care for itself for months at a time without attention. I attain these objects by means of the novel details in the construction and operation of the several parts of the mechanism which will be apparent from the detailed description hereinafter when read in connection with the accompanying drawings, forming part thereof, and wherein preferable embodiments of the invention are disclosed for the purpose of illustration.

In the drawings, Figure 1 is a vertical sectional view of a part of a windmill head in line with the center of the wheel shaft, other parts with a portion of the windwheel being shown in elevation; Fig. 2 is a view of a portion of the parts shown in Fig. 1 as seen when looking in the direction indicated by the arrow *x* in Fig. 1; Fig. 3 is an enlarged sectional view of fan 5 on a line like *k*—*k*'' in Fig. 2 showing a modified method of securing the fan to the rods 6 and 7; Fig. 4 is an enlarged sectional view of a modified form of a fan on a line like *k*—*k*' in Fig. 2 showing a flat instead of a curved fan, also showing the position of casting or governor connecting piece 4 relative thereto and the methods of securing the fan and casting to the rods 6 and 7; Fig. 5 is a view of the attachment 11 as seen in Fig. 4 in connection with parts adjacent thereto; Fig. 6 is a sectional view on line *c*—*d* in Fig. 5; Fig. 7 is a sectional view on line *a*—*b* in Fig. 5; Fig. 8 is an enlarged sectional view on a line like *k*—*k*' in Fig. 2; Fig. 9 is another sectional view on a line like *k*—*k*' showing another modified form or method of securing the fans or sails to the rods 6 and 7; Fig. 10 is a sectional view on line *s*—*s*' in Fig. 4 showing the method of securing the casting 4 to the rods 6 and 7; Fig. 11 is an enlarged detailed view of the spoke attachment 16; Fig. 12 is a side view

of the friction or brake wheel 23 which is shown in section in Fig. 1; Fig. 13 is a vertical sectional view in line with the center of the wheel shaft of a modified form of windmill head with bevel gear power transmission; Fig. 14 is an elevation of one of the fan sections and parts adjacent thereto of a modified form of windwheel; Fig. 15 is an enlarged side view of the inner end of fan 63' in Fig. 14; Fig. 26 is a sectional view on line $i-i'$ in Fig. 15; Fig. 17 is a vertical sectional view in line with the wheel shaft of another modified form of windmill head; Fig. 18 is a vertical sectional view on line 15 $m-m'$ in Fig. 17, looking toward the body part of the windmill head; Fig. 19 is a vertical sectional view on line $n-n'$ in Fig. 17 showing the hub of the windwheel and the friction or break wheel 23 as seen when looking 20 toward the body part of the incasement; Fig. 20 is an enlarged side view of an oil elevating device and a vertical sectional view through a covered oil receiver which are parts numbered as 40 and 37' in the right 25 hand part of Figs. 17 and 31; Fig. 21 is a view of the oil elevating vessel 40, looking at the side upon which the bracket 44 is attached; Fig. 22 is a view of the shive supporting bracket 49 as seen when looking at it 30 from the direction of the body part of the windmill head; Fig. 23 is a view of a modified form of a governing or speed regulating device as would be seen when looking in the direction indicated by the arrow y in Figs. 35 17 and 24; Fig. 24 is a view through parts of Fig. 23 in line with the center of the wheel shaft 18' showing some parts in section and other parts in elevation; Fig. 25 is a view of a portion of the parts shown in 40 Fig. 23 as seen when looking in the direction indicated by the arrow x' ; Fig. 26 shows a modification of parts shown in Figs. 23 and 24; Fig. 27 are an enlarged view of the upper end of the lever or mast 71, in Figs. 45 13 and 31, showing the arm 71' in its normal position relative to the lever or mast 71; Fig. 28 is a view of the interior of the incasement part B of Figs. 13 and 31 showing the preferable form for connecting up the 50 pull out device when the windmill is equipped with the automatic starting and stopping device as is shown in Fig. 31; Fig. 29 is a view of the leeward side of a section of wheel fans or sails in which the spring 51 and the excess of sail surface on one side of the pivot rod 13 constitute the entire speed 55 regulating mechanism of a simplified form of windwheel; Fig. 30 is a like view to Fig. 29 showing the weight 10 attached to the 60 inner portion of the fan section as an auxiliary speed regulating element; and Fig. 31 is a side view of the modified form of windmill head shown in section in Figs. 13 and 28, with parts broken away, and embodying 65 in operative form the wheel and governing

and oil supply mechanism of Figs. 1, 2 and 17, and the pull out device, power transmitting and automatic starting and stopping mechanism shown in Figs. 13, 27 and 28.

Similar letters and figures refer to similar and corresponding parts throughout the 70 several views.

The main frame or turntable of the windmill head constitutes an incasement which comprises the pivot portions D and D' the 75 body portion A and the cover portions B and B' as seen in Figs. 1, 13, 17 and 18 and is adapted to inclose the main frictional parts of the windmill head and the oil reservoirs from which they are lubricated; referring to Fig. 1 the wheel shaft 19 is tubular and carries within it the solid shaft 18 to which at its inner end the friction or break wheel 230 is rigidly secured, this 80 brake wheel is provided with the slot 29 through which the boss or projection 24 of the crank disk 22 is adapted to project so as to form a suitable anchorage for the wristpin 25, the slot 29 is of such length and form as to permit the brake wheel 23 to oscillate 85 or rock to the extent of near one sixth of a revolution independent of the crank disk, the metal at the ends of the slot striking the projection 24 terminates the movement in either direction, and to the outer end of the shaft 18 the sleeve 1 is rigidly secured, this 90 sleeve is preferably counter bored so as to slide with an easy working fit over the outer end of the wheel shaft 19 so as to abut with an easy working fit against the adjacent end 95 of the wheel hub C, the end of the sleeve adjacent to the wheel hub being provided with the radial arms 2 as shown in Figs. 1 and 2, to the extremities of which one end of the connecting rods 3 is attached, the other ends 100 being attached to the casting 4 of the several fan sections somewhat as shown in Figs. 1, 2 and 10 the casting 4 being secured to the binding wires or rods 6 and 7 of the fan sections; each fan section may comprise any desired number of fans but for convenience 105 only three fans (5, 5' and 5'') are shown as seen in Figs. 1 and 2, the fans of each section being rigidly bound together, preferably, by three or four wires but a greater number 110 may be used to advantage in the larger sizes of wheels, the manner of securing these binding rods or wires to the fans is substantially as shown in Figs. 1, 2 and 8 in which the wires are shown as being passed through 115 holes near the edge portions of the fans, the holes being shown as having been made with a sharp pointed punch which removes no metal but forces the metal out into an annular flange as shown in Fig. 8, in Fig. 9 the 120 wires are shown as resting in a crimped portion of the outer edges of the fans, and in both Figs. 8 and 9 the wires are either brazed or welded direct to the fans; Figs. 3, 4, 5 and 6 show other modified methods of securing 125

the wires to the fans in which the wires are brazed or welded to the clips or attachments 11 and 12 which are riveted to the fans.

5 The fans or sails of the several sections of the windwheel are so apertured as to permit the pivot rods 13 to extend through the sails of the respective sections near the center of gravity of the sections so as to facilitate the 10 action of the governor in regulating the speed of the wheel and the putting of the mill into and out of service. The rods 13 also serve as tension rods extending from one to the other of the outer ends of the 15 spokes giving rigidity to the spider or frame of the wheel, and are preferably secured to the spokes substantially as shown in Figs. 1, 11 and 30 with screw nuts as adjustment means for giving the proper tension to the 20 rods.

The outside fans or sails of each section are preferably provided with flanged sleeves as shown at 13' and 13'' in Figs. 1, 2 and 3 which serve as bearings for the fan sections 25 and provide a convenient and substantial means against which to adjust the collars 50 for securing the sections in their proper place on the rod 13, referring to Fig. 11 it is readily seen that the rod 13 may be either 30 removed or replaced by removing the nuts at the ends and drawing the rod out or inserting it in the direction indicated by the broken lines, and that when all of the rods are in place by tightening the nuts any 35 desired amount of tension may be given them so that a very light rod will serve the purpose, and that the extra tension gives extra tension and rigidity to all parts of the wheel, the spokes 17 and 17' are preferably made of 40 light tubular steel and the clips or attachments 16 are provided with a socket which fits upon the ends of the spokes.

The casting 4 (see Figs. 4 and 10) is secured near the center of the fan sections to 45 the binding rods 6 and 7 and the pivotal portion of the arm to which the end of the governing rod 3 is attached is of such distance from the pivotal rod 13 that when the 50 brake wheel 23 is rocked from one extreme of its range of action to the other, relative to the crank disk 22, the arm 2 of sleeve 1 will have a range of action just sufficient to cause the rod 3 to throw the fan sections full 55 out of the wind as seen in Fig. 1 at one limit of its range of action and full in the wind as seen in Fig. 2 at the other limit of its range of action; the spring 51 is secured at one end to the adjustable clip 52 on spoke 17 and to the arm 2 of sleeve 1 at the other end 60 and has sufficient tension and strength to hold the fan sections full in the wind at the speed at which it is desired to have the wheel run until there is sufficient wind to cause the wheel to exceed the desired speed when by 65 reason of the greater amount of fan surface

on the outside of the pivotal center lines of the fan sections the force of the wind will overcome the tension of the spring 51 and cause a tilting of the fan sections toward the position shown in Fig. 1, the amount of the 70 inclination of the fans from the plane of the wheel rim depending upon the relation between the excess of wind pressure on the outer portion of the fans and the strength of the spring 51. This spring is designed to be 75 of such strength and the outer and inner fan surfaces so proportioned that during a storm that would damage the wheel the spring tension will be overcome to such an extent that the fans will be thrown nearly or entirely 80 out of the wind and held in that position while the heavy wind lasts; 27 is a pull out wire or cord, attached at its upper end to the brake lever 231 which is pivotally secured to the inside of the incasement part 85 B, 251 is a brake shoe secured to lever 231 and is adapted to bear upon the brake wheel 23 when the lever 231 is drawn downwardly by the cord 27 which is adapted to extend operatively to a convenient position for the 90 purpose, 241 is a spring adapted to normally hold lever 23' so that the shoe 25' does not contact with the wheel 23; when it is desired to throw the fans out of the wind the cord 27 is drawn downward until the 95 brake shoe binds firmly upon the wheel 23 and is secured in that position holding wheel 23 against rotation which through the medium of the shaft 18 also holds the sleeve 1 and arms 2 against rotation and as the wind-wheel is caused to rotate by the force of the wind against the fans the fans will be drawn from a position in the wind to a position full 100 out of the wind as shown in Fig. 1 and by reason of the excessive friction, caused by 105 the setting of the brake, will remain out of the wind until the brake is released, when the tension of the spring 51 will cause the 110 fans to return into the wind and the wheel will rotate in a light wind with no retard. 115 frictional contact with any part of the governing mechanism until there is sufficient force of wind to partially overcome the tension of the spring 51, and when there is sufficient wind to do that there is such an abundance of power available that the friction of the governing mechanism is negligible; the working bearings of the governing mechanism and the wheel that cannot be reached by the automatic lubricating mechanism within the incasement are designed to 120 be extra large and made with an easy working fit so that the wear and friction of these parts is negligible, in the construction herein shown, without the use of any lubricant 125 after the first oiling given when the mill is first set up. The sleeve 1 is preferably lined with some kind of antifriction metal where it bears on shaft 19.

As an auxiliary governing device and a 130

more accurate speed regulator the sleeve 1 is provided with the two backwardly inclined and oppositely extending arms 1' and 1'' to which the sails or fans 2' and 2'' are adapted to be adjustably secured near their outer ends so that the speed of the wheel will be limited by the resistance of the air against the fans 2', the resistance of the air against these fans acting in conjunction with the force of the wind against the excessive fan surface outside of the pivotal line of the fan sections makes a very positive and sensitive governing force and by making the fans 2' of metal and rightly proportioning their weight their momentum and inertia acting in unison with the force of the wind and the resistance of the air as above described makes more accurate the speed regulating powers of the governing mechanism, by reason of the momentum carrying forward the sleeve 1 when by excessive load or less wind the wheel is suddenly retarded in its motion, thus instantly throwing the fans fuller into the wind just at the beginning of the retarding motion, and by reason of the inertia when by an exceedingly strong gust of wind the wheel starts forward with accelerated motion the lagging of the sleeve 1 will instantly act to pull the fans out of the wind immediately upon the increased force of the wind striking the fans of the wheel; in Fig. 17, 18 and 19 is shown a modified pull out or stopping mechanism by means of which the same construction of wheel and governing mechanism is made practical and operative in connection with a solid wheel shaft instead of the tubular shaft 19 shown in Fig. 1. In this construction the brake wheel 23 is mounted with a loose rotatable fit upon the wheel shaft 18' between the wheel hub C and the end of the main wheel shaft bearing and is rigidly fixed to and at such a distance from the arms 2 of the sleeve 1 by means of the connecting bars or rods 32 that the wind wheel hub C stands between the sleeve 1 and brake wheel 23, as shown in Figs. 17 and 31, with the connecting bars 32 passing between the spokes of the wind wheel, as shown in Fig. 19, in such manner that the brake wheel and sleeve with its arms 2 are rotatable to near one sixth of a revolution independent of the hub C of the wind wheel, the bars 32 striking the spokes of wheel C which serve as stops to limit the motion of the arms 2 so that at the limits of their range of action they will hold the fans full in or full out of the wind as described in connection with Figs. 1 and 2; the lever 23' in Fig. 17, which corresponds to 231 in Fig. 1 in its operation, is preferably a two part bifurcated bell crank lever fulcrumed to the lower part of the bracket 33 as shown in Figs. 17, 18 and 31; from its fulcrum at the lower part of the bracket 33 the lever 23' extends upwardly upon each side of and

unites above the main bearing of the shaft 18' and is provided at its upper portion with means for the attachment of the pull out bar or rod 27' as shown in Fig. 17 which is adapted to pass outwardly with an easy sliding fit through the sleeve portion 31 of the incasement part B and connect to the upper end of lever 23' and to connect at its inner end to the upper end of the pull out cord 27 which extends upwardly through the vertical aperture of the pivot portion of the turntable and passes over the shive 270, so that the operation of stopping or putting the fans of the wheel out of the wind is substantially the same as described in connection with the construction shown in Figs. 1 and 2.

In this construction of windmill the wheel and governing mechanism serve the purpose of the usual steering vane, and as the wheel is placed at a considerable distance to one side of the supporting bearing at the top of the tower and has no steering vane to balance it this necessitates the use of a balance weight as 48 in Fig. 17 which is supported to the windward of the wheel by the braces 48' and 48''.

The main frame of the windmill comprises a lateral extension 53 (see Fig. 17) which constitutes the bearing for the wheel shaft 95 and is provided with the supply oil duct 54 and the return duct 55, 28 is an endless chain adapted to ride upon the crank disk and to extend to the bottom of the oil reservoir 36'' so as to elevate oil onto the crank disk 22 from which a portion of it will flow into the oil duct 54 and lubricate the wheel shaft and what flows down on the side next to the pitman 26 will lubricate the pitman bearings.

In the upper portion of the tower cap D' there is formed the annular oil reservoir 56 into which the downwardly projecting annular flange 39 of the pivot portion D' projects and constitutes the main supporting bearing of the turntable, and the downwardly projecting annular flange 35 of the part D' overhangs and protects the reservoir 56 from snow and rain; the pipe 36 extends from within the reservoir 36'' into the reservoir 56 and serves as an overflow from 36'' and as a means for replenishing the supply of oil in reservoir 56; 37' (see Figs. 17 and 20) is a covered oil receiver and 37 is an oil conveying tube leading from the receiver 37' into the reservoir 36'', 40 seen in Figs. 17, 20 and 21 is an oil elevating can or vessel and is suspended from shives 47 (see Figs. 17 and 22) by means of cords 45' and 45'' which are attached to the bail 42 substantially as shown in Figs. 20 and 21 and are made to pass over shives 47 from the side next to the oil receiver 37' and are attached at their other ends to the opposite ends of the cross bar 46 (see Figs. 17 and 22) 130

and are of such length that when the bar 46 is up against the shives as shown in Fig. 22 the vessel 40 will swing at a convenient distance above the ground so as to be readily 5 filled and operated therefrom, the cord 45 is to be a convenient amount longer than 45' and 45" and is attached at one end to the eye 44 at the lower part of the vessel 40 and at the other end to the loop at the center of 10 the cross bar 46; the oil receiver 37' is rigidly suspended, so that the tube 37 inclines downwardly to the reservoir 36", and is covered with the pivoted lid 38 which is provided with the hook portion 38" substantially as shown in Figs. 17 and 20 so that when the oil vessel 40 is drawn up it will approach the hook 38" substantially as shown in the relative positions of these parts in Fig. 20 so that the wire loop 41 is readily 15 caused to engage the hook 38", when the loop engages the hook sufficient tension should be given cord 45 to hold the vessel in its upright position until the lid of the receiver has been raised to the position 20 shown in Fig. 17 when an excess of pull is given on the cords 45' and 45" which throws the vessel to the position shown in Fig. 17 so as to cause the discharge of its contents into the receiver from which it flows through 25 the tube 37 and is utilized to lubricate the different parts of the windmill as above described, thus it is seen that all of the principal bearings of the windmill head are automatically lubricated during their operation 30 from lubricant carried in reservoirs that are inclosed and that the supply of oil in the reservoirs can be replenished at any time during the operation of the windmill without the necessity of either tilting or climbing 35 the tower for the purpose. After the oil has been discharged from the vessel it is lowered until the cross bar 46 is drawn up to the position shown in Figs. 22 and 31 and to maintain the cords in a vertical position and prevent 40 their being blown against the tower a suitable weight as 45' may be suspended to the lower portion which will serve the purpose and leave them free to swing around the tower as the windmill head turns in response 45 to the changing directions of the wind.

Figs. 14, 15 and 16 show portions of a modified form of windwheel in which each of the fans or sails are so pivoted that the center lines of their pivotal parts radiate from the center of the wheel, each fan having two pivotal bearings, one near each end, which are connected, one to an inner and the other to an outer rim of the wheel, the 50 details of both the inner and outer bearings are shown in Figs. 15 and 16 in which 63' and 63" are separate parts of the fan which are held together by the cross bar or strap 65' which is provided near its central portion with means for securing the pivot rod

or stud 64" rigidly thereto, which is adapted to pivot in a hole through the rim of the wheel, and with the eye or loop 64 at one end to which the connecting rods 62 are adapted to have a working engagement, the 70 rods 62 are of such length that when the fan 63' stands in its inactive position the fans 63 and 63" are also held thereby in their inactive positions; 63' the center one of the fans of the section is provided at its 75 inner end with the loop or eye 64' to which one end of the rod 3 is connected the other end being connected to the arm 2 of the governor, thus it is readily seen that the same governing devices that are shown in connection with the different modifications of 80 this invention are equally applicable and effective in connection with the radially pivoted wheel fans.

Figs. 23, 24 and 25 illustrate another 85 modified form of governing or speed regulating device in which the arms 1" and the hub or sleeve 1 (which correspond to the parts of the same members in Figs. 1, 2 and 17) are made rigid with the wheel shaft 18 and are adapted to rotate in unison with the windwheel and not to oscillate independent thereof as does the device shown in Figs. 1, 2 and 17; in this form of governor the arms 1" are provided near their outer 90 end portions with the pivoted arms 57 which also comprise the extension 59' the arms 57 are adapted to carry at their outer extremities the fans 2' and to the other ends of arms 57 the spring 59 is attached in such 95 manner as to normally hold the end 59' against the stop 58' so that the fans 2' are held in such position that during their rotation they pass through the air edgewise thus offering substantially no resistance to 100 the motion of the windwheel during light winds; 57" are adjustable governor weights adapted to be rigidly attached at any desired position on arms 57, and 57' are adjustable 105 clips secured to arms 57 and are adapted to a pivotal engagement with one end of the connecting rods 3' which are adapted to be pivotally connected at their other ends to the radial arms 2 of the governor mechanism near the hub of the windwheel, which 110 mechanism is substantially the same as shown and described in connection with Fig. 17, the rods 3' being of such length that when the fans 2' stand in the positions shown in solid lines in Fig. 23 the rods 3 115 will be caused to hold the wheel fans full in the wind or their most active position; in operation the governor and windwheel rotate in the direction indicated by the arrows x" and as the speed of the wheel increases 120 the weights 57" by centrifugal force tend to swing out to the position shown in broken lines and in doing so they carry the fans 2' outward causing them to present an increasing surface area against which the resist- 125 130

- ance of the air acts with an increasing leverage, as they swing outward, in unison with the centrifugal force of the weights 57" as a governing force, so that when the arms 57 5 once start to swing outward it requires but a very slight increase of speed of the wheel to cause a turning of the wheel fans to near their inactive position as shown in Figs. 1 and 14.
- 10 Fig. 26 illustrates a modified form of the central portion of the speed regulating device shown in Figs. 23 and 24 in which the arms 1" and the sleeve or hub portion 1 to which they are rigidly attached are so mounted as to be adapted to oscillate independently of both the hub of the windwheel and the parts of the governing device that are made rigid with the radial arms 2; in this modification of the central parts of this 15 governor the key 72", see Figs. 23 and 24 is dispensed with and the part 1 which carries the arms 1" is left free to oscillate upon the shaft 18' said shaft being extended sufficiently beyond the part 1 to carry the dog 20 or stop device 60 as shown in Fig. 26 which is rigidly secured to the shaft, and the stop portions 3" are made to stand in the positions indicated by the broken lines at 3" in Fig. 23 and the solid lines in Fig. 26 relative to the arms 1" when the wheel is 25 standing with the fans in active position or when it is revolving with not sufficient speed to cause the governor to act; this position of the arms 1" relative to the stops 3" holds 30 the wheel fans full in the wind and the governor fans 2' in their inactive position as the fans 2' have a curvature that coincides with the curvature of the circle described by them as they revolve in this position; and 35 the purpose of this modification is to utilize the momentum and inertia of the governor parts as governing forces which in this construction acts at all times in unison with and augments the other forces as described 40 above which causes a more positive and commensurate response to the demands resulting from a changeable wind or varying load, and as this governor has considerable weight the inertia acts prior to the other forces 45 50 when the mill is starting and prevents speeding of the wheel when it is suddenly thrown into action, causing it to speed up slowly in a heavy wind.
- Referring again to Figs. 1 and 17 as a 55 construction for a cheap windmill the governor arms 1" and fans carried thereby may be dispensed with entirely in windmills for work that does not require a regular speed, producing a wheel and speed regulating 60 mechanism therefor which is made up of sections of fans or sails and connecting parts somewhat as shown by the illustration of a fan section in Fig. 29 which depends entirely upon the spring 51 and the excess sail surface on one side of the pivot rod 13
- for controlling the speed of the wheel; and Fig. 30 illustrates a cheap and simple but somewhat more efficient speed regulator which is produced by simply attaching the weight 10 to the inner portion of each of the sections of fans in the wheel as is otherwise shown in Fig. 29. But for special work that requires a certain speed and close regulation the special form of automatic starting and stopping and pull out device shown in Figs. 13, 27, 28 and 31 is provided and is so designed as to be operative, by means of slight modifications in connecting parts, in connection with any of the speed regulating devices herein described; in these figures the main frame or turntable is represented as comprising incasement parts, oil supplying devices and oil reservoirs which are similar to the corresponding parts described in connection with Figs. 1 and 17 70 and are marked by the same numbers so far as the corresponding parts go, but the incasement parts A and B are modified in form to meet the requirements of a geared or power mill as is shown in section in Figs. 13 and 30 75 80 85 90 95 100 105 110 115 120 125 130
- 31 in which 67 is the driving gear which is rigidly secured to the solid wheel shaft 18', and 67' is a smaller driven gear which is rigidly secured to the upper end of the vertical tubular shaft E'; the shaft E' extends downwardly in the tower and has a bearing in the beam 68 and carries the gear 68' which is in mesh with the gear 68" which drives the vertical shaft 69 which is designed to extend to and to actuate mechanism therebelow; thus providing an open space through the power shaft E' through which the pull out cord 27 may operate without contact with any of the moving parts of the power-transmitting mechanism.
- An integral part 78 of the incasement part A projects upwardly and surrounds and is concentric with the tubular shaft E' at its upper portion and is designed not to contact therewith the shaft being rigidly fixed in the gear 67' which is especially designed to encompass and have a close working fit upon the said upwardly projecting integral part of the incasement part A so that the frictional part thereof will be submerged in the oil in the reservoir 36"; and when the gear 67 is secured to a solid wheel shaft as is shown in Fig. 31 wherein the geared mill is illustrated as being governed by the speed regulating mechanism shown in connection with Figs. 1 and 17 and the pull out mechanism shown in Figs. 13 and 28.
- The pull out mechanism shown in Figs. 13, 27 and 28 comprises the cord or wire 27, 125 the two bell-crank levers 66' and 66", the connecting rod 27' shown in use in Fig. 28 and the rod 27" shown in use in Fig. 13; this device is to be connected up as shown in Fig. 13 when it is desired to use the mill 130

for special work requiring the use of the automatic starting and stopping device at times and at other times when it is desired to use the windmill without the automatic starting and stopping mechanism when it will be held out of service by drawing down the cord 27 and securing it so that the wheel sails will normally stand full in the wind so as to utilize all of the available force thereof on light work that does not require a regular motion; and when it is desired to run the mill exclusively on special work that requires a regular motion and to put the sails out of the wind when not on such work the rod 27' is to be connected as shown in Figs. 28 and 31 wherein the lever 66' instead of 66'' is caused to actuate the brake 23' in the opposite direction to that caused by the lever 66'' so that when the cord 27 is drawn down with this connection made the brake is set and the windmill caused to go out of action and remain so until the cord is released when the automatic starting and stopping device will be free again to utilize such winds as will give the required speed for the work to be done, the governor and controller mechanism having been previously adjusted accordingly.

The automatic starting and stopping mechanism comprises the mast 71 which is, preferably detachably, secured to the brake lever 23' and is provided at its upper portion with the casting 75 to which the arm 71' is pivoted somewhat as shown in Fig. 27 which shows this arm in its normal position relative to the mast 71 and in Fig. 31 wherein it is shown in the position to which it will be thrown when actuated by the wind force to which it has been adjusted, and 72 which is a sail carried by arm 71' and as shown in solid lines in Fig. 31 stands broad side to the wind but as shown in broken lines stands inclined to the windward in which position it presents less resisting surface to the wind. This feature of the automatic starting and stopping mechanism makes it necessary to have a stronger wind to start the sail from its normal position than it does to hold it in its upright position which is a construction which acts in harmony with the natural conditions under which a windmill works as it requires a stronger wind to start the mill under full load than it does to keep it moving after being fairly started, and the spring 72' is of such strength that when the wind has receded to that stage at which the work will not be properly done it will automatically throw the arm 71' and sail 72 to the position shown by the broken line Q and in this position the reduced wind pressure on the sail 72 is such that the spring 24' will actuate the brake lever 23' and throw the mast 71 to the position shown by the broken line Q' and set the brake 23' on the brake wheel 23 and hold it against rotation to the extent that with the motion of the wheel and wind force then prevailing the sails of the windwheel will be immediately turned entirely out of the wind and the wheel held against rotatable and oscillatory movement 70 on its axis until there is again sufficient wind force to throw the sail 72 to its upright position which is ample to properly operate the windmill with its attached load.

By the use of the two bell-crank levers 75 66' and 66'' this modified form of windmill is more perfectly adapted to be used on either the special work of the nature just described, or on any of the ordinary kinds of work to which a windmill may be adapted to accomplish, and when it is desired to fit the mill for general use it is only necessary to disconnect the rod 27'' and replace it by the longer rod 27' which is to be attached to the lever 66' as shown in Fig. 28 instead of to the lever 66'', and then to unhook the lower end of spring 24' from the bracket 66 and swing it up and hook it in the eye there above so that the spring acts the same as shown at 24' in Fig. 17, and after these two slight changes have been made the windmill will normally stand with the sails full in their active position instead of in their inactive position as before the changes were made; the arm 71' and fan 72 may be removed or not as desired as they do not affect the work of the wheel or the governor when the mill is equipped for ordinary work. With the mill equipped for automatic starting and stopping with the spring 24' hooked 100 to bracket 66 and the rod 27' attached to lever 66'' as shown in Fig. 13 the mill may be immediately put in condition for running on ordinary work by simply drawing down the pull out cord 27 so as to overcome the tension of spring 24' and securing it in that position, but generally it is more desirable to use this operation of the pull out cord to hold the sails in an inactive position, hence the employment of the two levers 110 instead of one.

Having thus described the invention, what I claim as new and desire to secure by Letters Patent, is—

1. The combination, in a windmill, of a rotatable hub portion, with spokes radiating from said hub portion, tension rods extending from one to the other of said spokes, a sail portion for each of said tension rods, and a tubular pivot portion for each of the said sail portions whereby said sail portions are adapted to oscillate upon said tension rods for the purpose set forth.

2. In a windmill, in combination, a wheel shaft, a windwheel provided with pivotally mounted fans or sails, a governor device in operative connection with the said fans or sails and oscillatorially mounted relative to the said wheel shaft, a brake member in operative connection with the said device,

governor fans adapted to actuate said device in one direction and a spring adapted to actuate the said device in the opposite direction, and means adapted to operate in connection with the said brake member whereby the said device may be held against rotation.

3. The combination, in a windmill, of a wheel carrying sails which are adapted to be turned to and from active and inactive positions, with mechanism adapted to normally hold said sails in their inactive position and to governingly actuate the said sails during the operation of said wheel, and a controller or starting device which is adapted in connection with a predetermined force or velocity of wind to cause the said sails to be turned to their active position.

4. The combination, in a windmill, of a wheel carrying a sail portion that is adapted to be turned to and from active and inactive positions, with mechanism which is adapted to normally hold said sail portion in its inactive position, and a controller device which is adapted in connection with a predetermined force or velocity of wind to cause the said sail portion to take an active position.

5. In combination, a main frame, a rotatable shaft, a windwheel provided with pivotally mounted sails, a governor member provided with outwardly extending arms carrying air resistible fans and so mounted as to be adapted to rotate with and to oscillate independent of the said rotatable shaft, a brake wheel mounted in rigid connection with said governing member, sail controlling rods in operative connection with the said governing member and said pivotally mounted sails, and means for holding the said brake member against rotation.

6. In combination, a main frame, a rotatable shaft, a windwheel provided with pivotally mounted sails, a governing device adapted to rotate with and to oscillate independent of said rotatable shaft and carrying air resistible governor fans, means in operative connection with the said device and wheel sails for tilting or oscillating the said sails, and means whereby the said governor device may be held against rotation.

7. In combination, a main frame, a rotatable shaft, a windwheel, a governing device adapted to rotate with and to oscillate independent of the said rotatable shaft, fan or sail sections operatively mounted each constituting a part of the said windwheel and all adapted to be actuated by the said governing device, a brake member adapted to rotate and to oscillate substantially in unison with the said device, and means normally held out of contact with but adapted to be so applied as to hold the said brake member against rotation.

8. In a windmill, in combination, a main

frame, a windwheel rotatably mounted and carried by said main frame, fan or sail sections each comprising two or more fans or sails and all together comprising the sail portion of said windwheel, a governing device rotatable with said windwheel, stay rods or wires extending from one to the other near the edge portions of the fans of each of said fan sections at widely separated points and rigidly secured thereto, and a connecting rod for each of said fan sections in operative connection therewith and with the said governing device.

9. In a windmill, in combination, a main frame, a windwheel rotatably mounted and carried by the said main frame, fan sections operatively mounted each comprising a plurality of fans and all together composing the sail portion of the said windwheel, spaced binding or stay rods or wires disposed near the opposite edge portions of and rigidly binding together the fans of each section, and means for automatically turning the sail surfaces of the said fan sections to or from the wind.

10. In a windmill, in combination, a main frame, a windwheel rotatably mounted and carried by said main frame, fan sections operatively mounted and comprising the sail surface of the said windwheel, a governing device carrying governing fans and adapted to rotate with and to oscillate independent of the said windwheel, connecting rods operatively attached to the said device and fan sections, a brake member in operative connection with the said governing device, and means whereby the said brake member may be held against rotation.

11. In a windmill, in combination, a main frame, a windwheel rotatably mounted and provided with pivotally mounted fans or sails, a governor part that is adapted to rotate with and to oscillate independent of the frame or skeleton part of the said windwheel, a yielding connecting part in operative connection with the said frame or skeleton part of said windwheel and the said governor part, governor fans so mounted in connection with the said governor part that the resistance of the air thereagainst and the momentum and inertia thereof are utilized as governing forces, and fan or sail actuating parts in operative connection with the said governor part and pivotally mounted fans or sails.

12. In a windmill, in combination, a main frame or turntable comprising a weather proof incasement for the frictional parts of the main power transmitting elements of the windmill head, a vertically apertured pivot portion by means of which said turntable is adapted to operate about a vertical axis, a vertically arranged rotatable shaft adapted to operate through the vertical aperture of said pivot portion, an upwardly extending

annular flange within said incasement encompassing said vertical aperture, and a power transmitting element journaled on the said annular flange and adapted to actuate said rotatable shaft for the purpose set forth.

13. In a windmill, in combination, a windwheel, pivotally mounted parts composing the sail portions of said windwheel, a governor part operatively mounted adjacent to the hub portion of said windwheel, actuating bars or rods in connection with the said pivotally mounted parts and governor part, oppositely extending arms which are adapted to rotate with said governor part, and a governing member secured to each of said arms and adapted during the operation of the windwheel to cause the said arms and governor part to governingly actuate the said pivotally mounted parts.

14. The combination, in a windmill, of a rotatable motor part comprising the hub and spokes of a windwheel, with motor sails carried by said spokes and adapted for active and inactive positions, a governor device adapted to rotate with and to oscillate independent of said rotatable motor part, air resistable governor sails carried by said device and so mounted as to stand at all times with one edge to the windward, connecting means whereby said air resistable sails and governor device may so actuate said motor sails as to regulate the speed of said windwheel, controlling or stopping mechanism which has no frictional contact with either said windwheel or governor device except when applied to put or hold said windwheel out of action, and means for operating or applying the said controlling or stopping mechanism so as to put the said windwheel out of action.

15. In combination, a windwheel comprising a plurality of pivotally mounted sails and adapted to rotate about a horizontally disposed axis, and a governor comprising an air resistible sail portion which is adapted to governingly actuate said pivotally mounted sails during the operation of the said windwheel, the plane of the said air resistible sail portions being at all times substantially at right angle to the plane in which the said windwheel moves in its rotation about said horizontally disposed axis.

16. The combination, in a windmill, of a windwheel carrying a plurality of oscillatory sail portions and adapted to rotate about a horizontal axis, with a governor sail portion which is adapted to rotate with said windwheel and to operate with the sail surface thereof substantially at right angle to the plane in which said windwheel moves during its rotation about said horizontal axis, and means whereby the said governor sail portion may governingly actuate said oscillatory sail portions during the rota-

tion of the said windwheel about said axis.

17. The combination, in a windmill, of a windwheel comprising pivotally mounted sail portions, with a governor part comprising arms or spokes for carrying governor sails and adapted to rotate with and to oscillate independent of said windwheel, the said governor sails, and a connecting bar for each of said pivotally mounted sail portions which is pivotally secured to and extends tangentially from said governor part near the axis of said windwheel whereby the said sail portions are actuated during the operation of the windwheel.

18. The combination, in a windmill, of a windwheel carrying oscillatory sail portions and adapted to rotate about a horizontal axis, a governor sail portion adapted to rotate with and to oscillate independent of said windwheel and to at all times be so positioned that the sail surface thereof is substantially at right angle to the plane in which said windwheel moves in its rotation about said horizontal axis, connecting means between said governor and oscillatory sail portions, and means whereby the resistance of the air against and the momentum and inertia of the said governor sail portion may be caused to act in unison as governing forces for governingly actuating the said oscillatory sail portions during the rotation of the said windwheel.

19. In combination, a main frame, a windwheel rotatably mounted and carried by said main frame, fans operatively mounted and composing the sail portions of said windwheel, a governor device adapted to rotate with and to oscillate independent of the central portion of the said windwheel, fan actuating bars or rods in operative connection with the said device and fans, governor weights and fans operatively mounted and carried by said sail portions and device respectively and adapted to rotate and to oscillate therewith, means whereby the sail surfaces of the said windwheel fans are normally but yieldingly held to the wind, and manual means whereby the said sail portions may be caused to take inactive positions.

20. The combination, in a windmill, of a sail section comprising a plurality of sails united in a rigid structure, with a tubular pivot portion fixed to said sail section, a pivot rod extending through said tubular portion, and sail section retainers against which the end parts of said tubular portion are adapted to abut.

21. In a windmill, in combination, a main frame, a windwheel carried by said frame, pivotally mounted fans composing the sail portions of said windwheel, a brake member, a governor part in operative connection with said member and fans, a brake adapted to normally hold said brake member against rotation, and automatic means

- adapted to be so actuated by a predetermined velocity or force of wind as to cause the release of the said brake member.

22. The combination, in a windmill, of a main frame, with a windwheel carried by said frame, pivotally mounted fans composing the sail portions of said windwheel, a brake member, a governor part in operative connection with said member and fans, a brake lever, a spring adapted to normally cause said lever to hold said member against rotation, an arm portion in operative connection with said brake lever and normally inclined to the windward, and a fan or sail portion carried near the free end of said arm portion.

23. In a windmill, in combination, a main frame, with a windwheel operatively mounted and carried by said frame, pivotally mounted fans composing the sail portions of said windwheel, a brake member, a governor part in operative connection with said member and fans, a brake lever, a spring adapted normally to cause said lever to hold said member against rotation, an extended arm operatively attached to said lever, and a sail or fan carried at the outer portion of said arm.

24. In a windmill, in combination, a main frame or turntable mounted to rotate about a vertical axis, a windwheel carried by said main frame, pivotally mounted fan sections composing the sail portions of said windwheel, governing mechanism adapted to control said fan sections, and means whereby said governing mechanism and fan sections may be automatically held in an inactive position until a predetermined velocity or force of wind causes the release thereof.

25. In a windmill, in combination, a main frame or turntable, a windwheel carried by said main frame, governing mechanism adapted to control the speed of the said windwheel, a lever and means in connection therewith for normally holding said governing mechanism and windwheel against rotation, and a sail or fan carried by said lever.

26. In a windmill, in combination, a main frame or turntable, a windwheel, governing mechanism adapted to control said windwheel, a lever and means in connection therewith for holding said mechanism and windwheel against rotation, and a sail or fan adjustably secured and carried by said lever for the purpose set forth.

27. In a windmill, in combination, a windwheel carrying oscillatory sail portions, governor sails adapted to rotate with said windwheel and to continuously maintain a position substantially edgewise to the wind, and means whereby said governor sails are adapted to automatically actuate said oscillatory sail portions during the rotation of the said windwheel.

28. In a windmill, in combination, a main frame or turntable, a windwheel carried by said main frame, fans pivotally mounted and composing the sail portions of the said windwheel, a governor device adapted to rotate with and to oscillate independent of the central portion of said windwheel, actuating bars or rods in operative connection with the said device and fans, governor fans carried by said device and adapted to rotate and to oscillate therewith, and means whereby the sail surfaces of the said sail portions are normally but yieldingly held to the wind.

29. In a windmill, in combination, a windwheel, a sail section comprising a plurality of sails united in a rigid structure and adapted to oscillate on a pivot rod, a tubular pivot portion, and adjustable retainers fixed upon said rod adjacent to the opposite end of said pivot portion.

30. The combination, in a windmill, of a main frame or turntable comprising an incasement portion and a vertically apertured pivot portion, with a rotatable motor part, a rotatable shaft vertically arranged and adapted to operate through said pivot portion during the operation of said turntable, means within the said incasement whereby said motor part is adapted to actuate said rotatable shaft, and means whereby lubricant may be stored and automatically used repeatedly in lubricating the frictional parts of said motor part and the said shaft actuating means.

31. In a windmill, in combination, a main frame or turntable comprising an incasement portion and a vertically apertured pivot portion by means of which it is adapted to rotate or oscillate about a vertical axis, an oil reservoir within said incasement, a vertically apertured bearing portion within said reservoir above and in alignment with the axis of said pivot portion, a vertical shaft extending from below through said pivot and bearing portions to the interior of said incasement, a gear rotatably mounted on said bearing portion and adapted to actuate said vertical shaft, and a rotatable motor part carried by said turntable partially within said incasement portion and adapted to actuate the said gear and vertical shaft during the operation of said turntable.

32. In a windmill, in combination, a main frame or turntable, an incasement portion, an oil reservoir, a vertically arranged tubular shaft, a horizontal shaft, a windwheel, and bevel gears rigidly fixed to said shafts and adapted to operate in contact with the lubricant contained in said reservoir.

33. In a windmill, in combination, a windwheel provided with sails adapted for active and inactive positions, governing mechanism adapted to rotate with and to oscillate independent of said windwheel and to automatically

cally turn said sails from their inactive and hold them in their active positions, a controller device adapted to normally hold said governing mechanism against rotation, and wind actuated means whereby a predetermined force or velocity of wind will free said governing mechanism from the holding effect of the said controller device.

34. In a windmill, in combination, a sail section comprising a plurality of sails having a series of pivotal apertures extending in alinement through all of the said sails, an apertured pivot portion secured to the said sail section with the aperture thereof in alinement with the said pivotal apertures, and a pivot rod extending through the apertures of the said sail section and pivot portion.

35. In a windmill, in combination, a rotatable shaft, spokes radiating from said shaft, a series of straight rods connecting the extremities of said spokes, means whereby any desired tension may be given to said rods, a plurality of sections of fans, apertures in alinement through all of the fans in each section whereby each of the said sections is adapted to be pivotally mounted upon one of said rods, and governing mechanism adapted to governingly actuate the said fan sections during the operation of the windmill.

36. In a windmill, in combination, a sail section pivotally mounted and comprising a plurality of sails radiating from a common center, pairs of binding wires or rods each of which is secured to all of said sails, the rods of each pair being secured to all of said sails and substantially equidistant from said common center.

37. In a windmill, in combination, a wind-wheel comprising a plurality of pivotally mounted sail sections, a plurality of sails and a plurality of tie wires or bars for each of said sections, said wires or bars being arranged some upon one and some upon the other of the longitudinal edge portions of said sails, and a speed regulating device whereby said sail sections may be governingly actuated during the operation of the windmill.

38. In a windmill, in combination, a wind-wheel comprising a plurality of sail sections operatively mounted and a plurality of sails and tie wires or bars in each of said sections, said sails radiating from a common center and said wires or bars being positioned substantially in arcs of circles concentric with said common center and secured some on one and some on the other of the longitudinal edge portions of all of the sails of their respective sections.

39. In a windmill, in combination, a sail section comprising a plurality of sails and a plurality of tie wires or bars arranged upon each side of the central plane of the section,

and means whereby each of the said wires or bars may be rigidly secured to all of the sails of the section.

40. In a windmill, in combination, a sail section comprising a plurality of sails, a plurality of tie wires or bars arranged upon each side of said section, and means whereby said wires or bars are secured in pairs with the wires or bars of each pair to the opposite longitudinal edge portions of the sails. 75

41. In a windmill, in combination, a sail section comprising a plurality of sails, means whereby said sail section is pivotally mounted as an actuating part of the wheel of the windmill, a pair of tie wires or bars 80 arranged one upon the leeward and the other upon the windward side of said section, a sail controlling member secured to both of said wires or bars, and governing mechanism in operative connection with the 85 said controlling member.

42. In a windmill, in combination, a sail section comprising a plurality of sails, with two sets or series of tie wires or bars one of the said sets or series being to the windward 90 and the other to the leeward of the central plane of the sails of the section, and flange portions integral with said sails for the purpose set forth.

43. In a windmill, in combination, a sail section comprising a plurality of sails and a plurality of tie wires or bars upon each the leeward and windward sides of the central plane of the sails of the section, and means whereby said section may be pivotally anchored and governingly actuated as an impelling part of the wheel of the windmill. 100

44. In a windmill, in combination, a main frame or turntable comprising a pivot portion by means of which it is adapted to rotate or oscillate about a vertical axis, a wind-wheel, controlling mechanism for said wind-wheel, a pair of bell-crank levers connected one with the other above said pivot portion, means by which one of said levers may be 105 connected with and adapted to actuate said controlling mechanism, and means extending below said pivot portion by which both of said levers may be actuated.

45. In a windmill, in combination, a main frame or turntable provided with a pivot portion whereby it is adapted to rotate or oscillate about a vertical axis, a windwheel, controlling mechanism for the said windwheel, a pair of bell-crank levers adapted to 110 be actuated one by the other, and means in connection with the said levers and mechanism whereby the said mechanism may be optionally manipulated by a person stationed below said pivot portion. 115

46. In a windmill, in combination, a wind-wheel, a speed regulating device adapted to governingly actuate said windwheel during its rotation, a pivoted lever, means whereby said lever may be actuated in one direction 120 125

and caused to normally hold said device and windwheel inactive, and a sail portion whereby in connection with a predetermined force or velocity of wind the said lever may 5 be actuated in another direction and caused to effect the release of the said device and windwheel.

47. In a windmill, in combination, a windwheel carrying a plurality of sections of 10 pivotally mounted sails, a speed regulating device adapted to governingly actuate all of the sails of said sections during the operation of the said windwheel, mechanism adapted normally to cause the said pivotally 15 mounted sails to be held inactive, and a fan or sail which is adapted in connection with a predetermined force or velocity of wind to cause the said pivotally mounted sails to go into active service, said fan or sail being so 20 disposed as to stand more squarely to the wind during the time that said pivotally mounted sails are in their active than while they are in their inactive position.

48. In a windmill, in combination, a 25 windwheel, a speed regulating device adapted to governingly actuate said windwheel during its operation, mechanism acting in conjunction with said device whereby said windwheel is normally held inactive, an 30 arm or pivoted lever comprising a part of said mechanism and inclined to the windward, and another lever pivoted near the windward end of the said arm or pivoted lever and carrying a fan or sail for the purpose set forth.

49. In a windmill, in combination, a windwheel comprising sail portions that are adapted for active and inactive positions, mechanism adapted to normally hold 40 said sail portions in their inactive positions, a pivoted mast adapted to actuate a part of said mechanism, and a sail carried by and pivotally anchored to said mast.

50. In a windmill, in combination, a wind- 45 wheel, pivotally mounted sail portions constituting a part of said windwheel, friction or brake mechanism and suitable connections which are normally adapted to cause said sail portions to take their inactive positions, and means in operative connection with said brake mechanism whereby a predetermined force or velocity of wind will cause the said sail portions to take their active positions.

51. In a windmill, in combination, a sail 55 section comprising a plurality of sails, a plurality of tie or cross bars each of which is rigidly fixed to all of said sails, a tubular pivot portion for said sail section, and a 60 fixed pivot rod passing through and upon which the said pivot portion is adapted to oscillate.

52. In a windmill, in combination, a main

frame or turntable, a windwheel comprising pivotally mounted sail portions, a governor 65 part adapted to normally hold said sail portions in an active position, a controller device adapted to normally hold said governor part and sail portions in their inactive positions, and mechanism responsive to the force 70 of the wind whereby a predetermined force or velocity of wind will so actuate said device as to cause the said governor part and sail portions to take active positions.

53. In a windmill, in combination, a 75 main frame or turntable comprising an incasement portion and a vertically apertured pivot portion whereby it is adapted to rotate or oscillate about a vertical axis, a rotatable motor part, a vertically arranged 80 rotatable shaft adapted to operate through the vertical aperture of said pivot portion, gears meshing together and adapted to transmit motion from said motor part to said vertically arranged shaft, and means 85 whereby lubricant may be stored and automatically used repeatedly and substantially without wastage in lubricating the bearing portions of said gears and said motor part.

54. In a windmill, in combination, a main 90 frame or turntable comprising a weather proof incasement for the frictional parts of the main power transmitting elements of the windmill head, a vertically apertured pivot portion by means of which said turntable is adapted to operate about a vertical 95 axis, a vertically arranged rotatable shaft adapted to operate through the vertical aperture of said pivot portion, an oil reservoir surrounding said shaft and vertical aperture, and an actuating element attached to the upper end of said shaft for the purpose set forth.

55. In a windmill, in combination, a main 105 frame or turntable comprising a weather proof incasement for the frictional parts of the main power transmitting elements of the windmill head, a vertically apertured pivot portion by means of which said turntable is adapted to operate about a vertical 110 axis, a vertically arranged rotatable shaft adapted to operate through the vertical aperture of said pivot portion, an upwardly projecting annular flange in the lower portion of said incasement encompassing said rotatable shaft and forming the retaining walls of an oil reservoir, and a gear wheel secured to the upper part of and adapted to actuate the said vertically arranged rotatable shaft.

In testimony whereof I have signed my 120 name to this specification in the presence of two subscribing witnesses.

WILLIAM P. BRETT.
